UNITED STATES PATENT OFFICE.

EMIL F. HOLINGER, OF NEW YORK, N. Y., ASSIGNOR TO CHASE APPLIANCE CORPORATION, OF NEW YORK, N. Y., A CORPORATION OF NEW YORK.

ANTICREEPING DEVICE FOR RAILWAY RAILS.

Application filed January 12, 1928. Serial No. 246,204.

The invention relates to that class of anti-creepers or rail anchors, in which a rolling member interposed between the edge of the base flange of the rail and an adjacent fixed 5 surface on the tie-plate is engaged or crimped between such edge and surface by the longitudinal movement of the rail relatively to the tie-plate.

The object of the invention is to provide 10 means for holding the rolling member in engagement with the tie-plate and for resisting vertical movements of such member relatively to the rail and tie-plate.

The invention consists in certain novel 15 features of construction and arrangement by which the above objects are attained, to be hereinafter described and claimed.

The accompanying drawings form a part 20 of this specification and show an approved form of the invention.

Figure 1 is a plan view showing a portion of a rail supported upon and engaged with the improved tie-plate and roller.

Figure 2 is a vertical section taken on the 25 line 2—2 in Figure 1, and partly in elevation.

Figure 3 is a vertical section taken on the line 3—3 in Figure 1 and at a right angle to Figure 2.

Figure 4 is a plan view of a portion of the 30 tie-plate alone, corresponding to Figure 1 with the rail and roller omitted.

Similar reference numerals indicate the same parts in all the figures.

The rail may be understood to be of the 35 usual type having the head 5, vertical web 6 and inside and outside base-flanges marked respectively 7 and 8, supported on a tie-plate 9 of peculiar construction and held in place thereon and to the tie, not shown, by spikes 40 10 or other approved means.

On the upper face of the tie-plate, near one end, is a transverse abutment 11 extending parallel with the outer base-flange 8, serving to hold the rail against outward 45 lateral movement, and on the upper face of the tie-plate, oppositely disposed to the abutment 11 is a transverse shoulder on ridge 12 separated from but lying closely adjacent to and parallel with the inner base-flange 7.

50 In the midlength of the ridge 12 is a depression or recess 13 adjacent the base-flange 7, shown as rectangular in outline and extending in depth to the main surface of the tie-plate 9, and on the vertical face of the

cavity opposite the base-flange 7 is a rack 14 55 extending the length of such face.

The rolling member 15 lies in the space between the rack 14 and edge of the base-flange 7 and is elliptical in plan with its periphery perpendicular to its base and is formed with 60 vertical teeth 16 adapted to mesh with the teeth of the rack 14. It is preferably of high manganese steel harder than the rail, so that its teeth 16 will bite slightly into the edge of the base-flange 7.

On the base of the elliptical member 15 and integral therewith is a centrally located cylindrical stud 17 which is received in a slot 18 in the bottom of the cavity 13 and matching closely therein.

The minor diameter of the outer periphery of the toothed roller 15 is the same, or preferably slightly greater than the width of the space between the base-flange 7 and the roots of the teeth of the rack 14, and the roller is inserted in such space by entering the stud 17 into the slot 18 and engaging the teeth 16 of the roller with the rack and also frictionally with the edge of the base-flange 7; 75 it is then forced down until it rests upon the floor of the cavity 13 with its stud 17 lying in the slot 18 and in a vertical position.

Thus engaged the longitudinal movement of the rail induces the desired strong frictional bite or pinching action to increase, 80 with the result that the movement of the rail is effectually checked, and by the engagement of the teeth of the roller with the teeth of the rack the roller is compelled to make the partial rotation required to effect the 85 pinching action and the danger of slipping or sliding movements of the roller relatively to the tie-plate is eliminated.

The function of the stud 17 and the slot 18 is to hold the roller against vertical movement. It will be noted that the slot is slightly curved to permit the stud to follow the curvilinear path described by the axis of the ellipse in its movements, with the result that the periphery of the stud is maintained in 90 close contact with the side walls of the slot. Any tendency of the roller to tilt caused by a lifting movement is thus resisted by the corresponding tendency of the stud to cramp between the confining walls of the slot, and 95 as the lifting strains always are in the direction to tilt the roller the latter is effectually held against such rising movement.

I claim:—

1. In an anticreeping device, a tie-plate adapted to support a rail, means on such plate for engaging the outer base-flange of such rail to hold the latter against lateral movement, a surface on said plate adjacent to and separated from the inner base-flange of said rail, a rolling member located in the space between said inner base-flange and said surface, adapted to engage frictionally with said inner base-flange and to increase such frictional gripping action by the movement of said rail longitudinally, and a stud on said rolling member received in a slot in said tie-plate.
2. In an anti-creeping device, a tie plate adapted to support a rail, means on such plate for engaging the outer base-flange of such rail to hold the latter against lateral movement, a rack on said plate adjacent to and separated from the inner base-flange of said rail, a toothed rolling member located in the space between said inner base-flange and said rack and in mesh therewith, adapted to engage frictionally with said inner base-flange and to increase such frictional gripping action by the movement of said rail longitudinally, and a downwardly projected stud on said rolling member received in a slot in said tie-plate.
3. In an anticreeping device, a tie-plate adapted to support a rail, an abutment on

said plate adapted to lie against the outer base-flange of said rail, a ridge on said plate adjacent the inner base-flange of said rail, a recess in said ridge adjacent said rail, a rack in said recess opposite said inner base-flange, a toothed elliptical rolling member located in such recess, in mesh with said rack and adapted to engage frictionally with said inner base-flange, and a downwardly-projected stud on said rolling member received in a slot in said tie-plate.

4. In an anticreeping device, a tie-plate adapted to support a rail, an abutment on said plate adapted to lie against the outer base-flange of said rail, a ridge on said plate adjacent the inner base-flange of said rail, a recess in said ridge adjacent said rail, a rack in said recess opposite said inner base-flange, a toothed elliptical rolling member located in such recess, in mesh with said rack and adapted to engage frictionally with said inner base-flange, and a downwardly projected cylindrical stud centrally located on the underface of said rolling member, said tie-plate having a slot therein in such recess, said slot adapted to receive said stud, and curved to conform to the movements of the latter and said rolling member.

In testimony that I claim the invention above set forth, I affix my signature hereto.

EMIL F. HOLINGER.
